VINCENT A. BIANCO, OF CULVER CITY, CALIFORNIA

NECKTIE

Application filed March 19, 1930. Serial No. 437,078.

My invention pertains to a necktie of the four-in-hand type, having to do with the mechanical construction of the necktie.

If neckties of the four-in-hand type, difficulty has been experienced in the pressing of such neckties, especially after cleaning in properly pressing or ironing the necktie without causing creases and this is largely due to the manner in which the lining fabric is attached to the fabric forming the body portion of the tie. My invention pertains to a new manner of attaching the lining material so that the lining will remain in place in the tie and thus to a great extent prevent wrinkling of the tie when in use and enable pressing to be done leaving the tie in a smooth finished condition.

In forming neckties therefore I utilize a strip of lining which is narrower than the fabric that forms the tie. This strip is stitched to the fabric of the tie on the marginal edges of the lining, the stitches extending through the material of the tie. The body or outside material of the tie is then folded and its marginal edges stitched together in the usual manner forming a complete tie with the stitching securing the lining being on the back of the tie so that it is not observable when the tie is being worn.

My invention is illustrated in the accompanying drawings, in which,

Figure 1 is a view of the strip of fabric forming the tie with the lining strip stitched thereto, both being illustrated as flat;

Fig. 2 is a cross section of the fabric of the tie and the lining when stitched together and before folding;

Fig. 3 is a cross section of the tie with the marginal edges of the fabric of the tie stitched together, the tie being inside out;

Fig. 4 is a cross section of the finished tie looking at the back of the tie;

In the drawings, the fabric strip of the tie is indicated by the numeral 11, this forming the back and having the usual shape of a tie,

being broader at one end 12 than at the other end 13 and having a narrow neck portion 14. The lining strip 15 is formed of the same general shape as the strip of tie material but is narrower and shorter. The lining and the fabric of the tie are stitched together by stitches 16 and 17 passing through both strips of material adjacent the margins of the lining strip. The ends of the lining strip and the tie indicated at 18 however are not stitched. After the above stitching the tie is folded inside out and the marginal edges 19 of the fabric of the tie are stitched by longitudinal stitches 20. This forms the tie into a tube with a lining on the outside (note Fig. 3). The tie is then turned right side out which brings the stitches 16 and 17 on the back of the tie and the seam 21 of the marginal edges is at the center portion of the back.

It will be seen by this construction that the lining has a fold 22 along each side edge 23 of the finished tie and on the inside with the stitching on the back of the lining. This holds the lining in correct position in regard to the structure of the tie. The lining being thus firmly held at opposite sides to a great extent eliminates wrinkling of the tie and also in pressing creasing is eliminated to a great extent.

Various changes may be made in the principles of my invention without departing from the spirit thereof as set forth in the description, drawings and claim:

I claim:

A necktie having an elongated strip forming the outside of the tie, such strip having its marginal edges stitched together and forming in effect a tube, such tube being flattened with folds forming the side edges of the tie with the stitching on the back of the tie, an elongated lining strip fitted inside of the outside tube and against the inside of the front portion of said tube, said lining strip having folds adjacent its sides turned toward

the back of the tie inside the folds of the tube, the marginal edges of the lining strip being stitched to the back of the tube adjacent the side edges of such tube, leaving a space between the marginal edges of the lining strip and the stitching of the outer strip without any interlining directly bearing thereagainst.

5 In testimony whereof I have signed my
10 name to this specification.

VINCENT A. BIANCO.
